UNITED STATES PATENT OFFICE.

JOHN D. OWENS, OF MARION, OHIO.

FURNACE FOR LIMEKILNS OR OTHER STRUCTURES.

SPECIFICATION forming part of Letters Patent No. 793,392, dated June 27, 1905.

Application filed April 15, 1903. Serial No. 152,661.

To all whom it may concern:

Be it known that I, JOHN D. OWENS, a citizen of the United States, residing at Marion, in the county of Marion and State of Ohio, have 5 invented certain new and useful Improvements in Furnaces for Limekilns or other Structures, of which the following is a specification, reference being had therein to the accompanying drawings.

- 10 This invention relates to an improved furnace for limekilns and other structures, the same being devised more particularly for use in connection with the burning of lime, although capable of use in other connections. 15 The invention has for its object to provide a furnace for burning soft or bituminous coal in such a way that practically all of the fuel will be utilized and a long flame will be produced of a character such that too great a 20 temperature will not result at the eye of the furnace.

To these ends the invention consists in certain novel features, which I will now proceed to describe and will then particularly point 25 out in the claims.

In the accompanying drawings, Figure 1 is a vertical sectional view of a limekiln embodying my invention, the same being in section on the line xx of Fig. 2 and looking in 30 the direction of the arrows. Fig. 2 is a plan section taken on the line yy of Fig. 1 and looking in the direction of the arrows, and Fig. 3 is a vertical section taken on the line zz of Fig. 2 and looking in the direction of 35 the arrows.

Heretofore lime has been burned in kilns consisting of a main chamber, in which the lime to be burned is charged, having a door near the bottom for the withdrawal of the 40 burned lime and furnaces located a suitable distance above the bottom of the kiln and communicating with the chamber thereof by eyes, so as to cause the products of combustion to enter said main chamber some distance above 45 the bottom. These furnaces as ordinarily constructed consist of a chamber divided by grate-bars into an upper and a lower section, the upper section constituting the combustion-chamber and the lower section the ash-

pit. The entire chamber is located above the 50 floor-line or ground-line adjacent to the kiln, and each section of the chamber has a door or closure, fuel being charged in through the upper door and the ashes withdrawn through the lower door. Air to support combustion 55 is admitted through one or both doors, and when admitted through the lower door it passes directly in a cold state to the grate-bars and through them to the fire, no combustion being maintained in the ash-pit. 60 With this structure wood has been considered the ideal fuel by reason of the character in temperature and length of the flame produced by its combustion. It is necessary that the heat should not be too great where the flame 65 enters the main chamber of the kiln through the eye of the furnace to prevent overburning of the lime at that point, and it is also necessary that the flame should extend upward through the material in the kiln a distance sufficient to thoroughly burn the stone 70 without overburning it to a height above the fire-line sufficient to fill the part of the kiln below the fire-line. In this way when a charge is withdrawn from the lower part of the kiln 75 the stone which descends to fill said space will all be properly burned, and after supporting the superincumbent mass while it is being burned to the proper degree may be then withdrawn. Owing to the scarcity of 80 wood as fuel, a substitute therefor has been sought and attempts have been made to burn soft or bituminous coal in the ordinary kiln-furnace. The results, however, have been unsatisfactory, because if the temperature is 85 sufficiently high to cause a flame long enough to reach to the desired height within the kiln the temperature is too high at the eye of the furnace and the lime at that point is overburned. In fact, the temperature may be such 90 as to burn the stone too hard at the eye without burning it to a sufficient extent above the eye. Therefore a portion of the charge would be overburned and another portion of the charge sometimes not sufficiently burned. A 95 further disadvantage of this coal is that a large portion of it forms into coke upon the grate-bars and no longer gives the desired flame, so

that it must be withdrawn unconsumed from the furnace and its place supplied with fresh fuel.

In the accompanying drawings I have shown 5 one form of apparatus adapted for use in carrying out my invention.

In said drawings, 1 indicates the body of the kiln, and 2 the main chamber thereof, in which the limestone is charged.

10 3 indicates the floor or ground line, and 4 an opening near the bottom of the kiln, through which the burned charges are withdrawn. The base of the kiln has a recess 5 formed in it (indicated in dotted lines in Fig. 2) to give 15 access to the opening 4.

The furnaces, as usual, are in duplicate and each consists of a combustion-chamber 6, having at one end a feed-door 7 and at the other end an eye 8, opening into the chamber 2. 20 The bottom of the main portion of the combustion-chamber is formed of grate-bars 9, located a sufficient distance apart to give an adequate air-supply to the bed of fuel resting on them and to permit particles of the fuel to fall through unconsumed. In practice I have found that an opening of one inch between the grate-bars at the top thereof is sufficient for this purpose, the openings increasing downwardly in width to prevent clogging. A 25 flue or passage 10 extends downward from the combustion-chamber into the base of the kiln, and one of the walls of said flue or passage, preferably that nearest the chamber 2, is inclined on a gradual slope downward and outward, as indicated at 11, and its surface is roughened or formed with projections to retain the fuel thereon. Each passage 10 communicates at its lower end with a chamber 12, located at a considerable distance below the 30 main combustion-chamber and having a floor or bottom 13, on which the dropping fuel accumulates. The floor or bottom 13 is imperforate or closed, so that the air-supply passes over and not through the fuel lying thereon, 35 and the combustion-chamber 18 is located laterally with respect to the combustion-chamber 6, so as to give the necessary extent and slope to the wall 11 of the flue or passage 10 to permit the formation thereon of an extended inclined fuel-bed, the said flue or passage 10 being so constructed as to cause the commingled gas and products of partial combustion arising from the chamber 12 to pass over 40 said inclined bed of fuel. A passage 14 (indicated in dotted lines in Fig. 2) leads from the chamber 12 to the atmosphere, preferably at the front of the kiln. Valves 15, mounted on rock-shafts 16 in each passage 10 immediately below the grate-bars, serve to regulate 45

60 the supply of air and gases to the main combustion-chamber, and provision may be made by means of sliding doors 17 for the regulation of the admission of air to the passages 14. It will be noted that the valves 15 are so arranged

that, while they control the supply of air and 65 gases to the main combustion-chamber, they insure the equal distribution of said supply throughout the entire length of said main combustion-chamber.

The apparatus being thus constructed, the 70 operation is begun by the lighting of a comparatively thin bed of soft coal on the grate-bars 9. A portion of this fuel falls through between the grate-bars in a partially-consumed and still-burning condition, and these 75 particles fall upon the inclined wall 11, some of them lodging there, while others pass down into the chamber 12 and accumulate on the floor 13 thereof. A slow smoldering or partial combustion of the fuel upon the floor 13 80 is maintained, so as to form an auxiliary bed of fuel below the main bed, and a similar bed of smoldering fuel is maintained along the inclined wall 11. The air enters in large volumes through the passage 14 and maintains 85 the desired combustion at the lower fuel-bed, over which it passes, carrying up along with it the gases produced by said partial combustion. Other gases are gathered from the inclined fuel-bed 11 in the flue or passage 10, 90 and as said flue or passage is maintained at a relatively high temperature the mixture of air and gases reaches the main fuel-bed in a highly-heated condition and can be seen jetting up through the same in vigorous combustion. This results in the production of a long flame extending upward in the interior of the main chamber of the kiln to the desired distance and having a temperature such as to properly burn the stone therein without overburning. The fuel in the main combustion-chamber is practically all consumed except 95 that portion thereof which falls through the grate-bars, and said fuel does not coke upon the bars and have to be removed. If the 100 dropping particles accumulate too rapidly in the lower combustion-chamber, they may be either recharged in the main combustion-chamber or burned elsewhere.

In practice I have found that by the use of 110 this structure a material saving in cost of production may be made both over the old wood process and the old coal process. There is also a material gain over the old structure in that none of the stone is overburned or underburned. It is also possible by my improved structure to materially increase the 115 output, if necessary, by "forcing" the kiln without damaging the product.

It is obvious that the furnace above described 120 may be utilized for other purposes than the burning of lime, it being adapted for use wherever a flame of the character produced thereby is required.

I make no claim in this application to the 125 process hereinbefore described, as the same forms the subject-matter of a separate application filed of even date herewith.

Having thus fully described my invention, what I claim as new, and desire to secure by Letters Patent, is—

1. In a soft-coal furnace for limekilns, an upper main combustion-chamber, having a flame-outlet and a charging-door, the floor of said chamber being formed of grate-bars spaced as described, a lower auxiliary combustion-chamber having an imperforate floor to support the partly-burned fuel falling from the upper chamber, said auxiliary chamber being laterally offset with respect to the upper combustion-chamber, so as to be outside the downward extension of its lateral boundaries, a passage extending upward from the lower chamber to the lower end of the upper chamber, said passage having an inclined or sloping wall extending under the entire grate-surface of the upper chamber and constructed and arranged to maintain thereon an inclined bed of fuel formed by the droppings from the upper chamber, and an air-supply conduit arranged to conduct air from the exterior over the fuel in the lower chamber to the upwardly-extending passage, said air-supply conduit constituting the sole source of supply of air to the fuel, and said upwardly-extending passage conducting the air and gases from the lower chamber over the inclined bed of fuel and delivering all of the resulting mixture below the grate of the upper chamber, substantially as described. 45
2. In a soft-coal furnace for limekilns and other structures, an upper main combustion-chamber having a flame-outlet and a charging-door, the floor of said chamber being formed of grate-bars spaced as described, a lower auxiliary combustion-chamber having an imperforate floor to receive the partly-burned fuel falling from the upper chamber, a passage extending upward from the lower chamber to a point below the grate of the upper chamber, an air-supply conduit arranged to conduct the air from the exterior over the fuel in the lower chamber to the upwardly-extending passage, whereby said upwardly-extending passage conducts the air and gases from the lower chamber to the under side of the grate of the upper chamber and constitutes the air-supplying means for the upper chamber, means located within said upwardly-extending passage below the grate to regulate the amount and equalize the distribution to said grate of the air and gases, and means independently controlling the admission of air through the air-supply conduit, substantially as described. 50
3. In a soft-coal furnace for limekilns and other structures, an upper main combustion-chamber having a flame-outlet and a charging-door, the floor of said chamber being formed of grate-bars spaced as described, a lower auxiliary combustion-chamber having an imperforate floor to receive the partly-burned fuel falling from the upper chamber, a passage extending upward from the lower chamber to a point below the grate of the upper chamber, an air-supply conduit arranged to conduct the air from the exterior over the fuel in the lower chamber to the upwardly-extending passage, whereby said upwardly-extending passage conducts the air and gases 55 from the lower chamber to the under side of the grate of the upper chamber and constitutes the air-supplying means for the upper chamber, means located within said upwardly-extending passage below the grate to regulate the amount and equalize the distribution to said grate of the air and gases, and means independently controlling the admission of air through the air-supply conduit, substantially as described. 60
